UNITED STATES PATENT OFFICE.

LAURENCE J. McDONALD, OF PHILADELPHIA, PENNSYLVANIA, ASSIGNOR
TO JOHN C. GRAHAM, OF SAME PLACE.

DESIGN FOR FRINGE.

SPECIFICATION forming part of Design No. 18,094, dated July 25, 1882.

Application filed June 10, 1882. Term of patent 14 years.

To all whom it may concern:

Be it known that I, LAURENCE J. McDONALD, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of pendants, B, of substantially-cylindrical contour, each composed of chenille threads twisted helically about the axis of the pendant and projecting loosely therefrom. The fringe is ornamented by presenting the appearance or effect of a series of figures of triangular outline, having their points or apexes located alternately at the heading and at the opposite side of the fringe, said figures being formed by the use of warp-threads of two different colors, so woven that a figure of one color having its point on one side of the fringe shall be inter-

posed between two figures of another color having their points on the opposite side of the fringe, the imaginary lines of the inclined sides of the figures being thus defined by the presence of different quantities of threads of each color in the several pendants, through which said imaginary lines extend.

It is not material in the design whether the pendants be plain or striped, so long as the effect of a series of triangular figures alternately differing in predominating color is preserved.

I claim—

A design for fringe, consisting of a heading and a series of chenille pendants ornamented by figures of triangular outline, of alternately-different colors and arranged in alternately-reversed positions, substantially as set forth.

LAURENCE J. McDONALD.
